UNITED STATES PATENT OFFICE

JULIUS P. HEIL AND CHARLES G. EISENBERG, JR., OF MILWAUKEE, WISCONSIN, AS
SIGNORS TO THE HEIL CO., OF MILWAUKEE, WISCONSIN, A CORPORATION OF WIS-
CONSIN

HORIZONTAL HOIST

Application filed October 5, 1928. Serial No. 310,661.

This invention relates to improvements in horizontal hoists, of the hydraulic type, and more particularly, although not solely, adapted for operating dump bodies of power driven 5 trucks or other vehicles.

It is one of the objects of the present invention to provide a hoist of the hydraulic type in which the power cylinder is in approximately a horizontal position and may 10 be used in connection with any standard make of truck and dump body.

A further object of the invention is to provide a horizontal hoist which will permit the 15 positioning of the body with relation to the front and rear axles of the truck, to more evenly distribute the load thereon and thereby increase the capacity of the truck.

A further object of the invention is to provide a horizontal hoist which is a unitary 20 structure, and is self-contained, and has therefore a minimum number of parts and may be easily mounted on a truck.

A further object of the invention is to provide a horizontal hoist which will automatically 25 stop the further tilting of the truck body when said body reaches its predetermined dumping inclination.

A further object of the invention is to provide a horizontal hoist in which a series of 30 levers are used in connection with a power cylinder for tilting the body of the truck.

A further object of the invention is to provide a horizontal hoist which may be used 35 with two power cylinders, but is more particularly adapted for use with a single power cylinder.

A further object of the invention is to provide a horizontal hoist having a single 40 power cylinder and a means for equalizing the strain on the cylinder piston and connected levers.

A further object of the invention is to provide a horizontal hoist which is arranged to 45 automatically stop when the piston has reached its outermost position.

A further object of the invention is to provide a horizontal hoist of the hydraulic type 50 in which provision is made within the cylinders for taking care of the excess oil when the piston is in its innermost position.

A further object of the invention is to provide a horizontal hoist of the fluid type having means for by-passing the oil from one side of the piston to the other to permit the piston to initially move inwardly. 55

A further object of the invention is to provide a horizontal hoist which is of simple construction, is strong and durable and is well adapted for the purpose described.

With the above and other objects in view, 60 the invention consists of the improved horizontal hoist and its parts and combinations as set forth in the claims and all equivalents thereof.

In the accompanying drawings in which 65 the same reference characters indicate the same parts in all of the views:

Fig. 1 is a side view of a motor truck having the improved horizontal hoist mounted thereon, parts broken away and other parts 70 being shown in section, the view also illustrating by dotted lines the body portion of the truck in its upper position;

Fig. 2 is a top view of a portion of the truck body and the horizontal hoist mounted thereon; 75

Fig. 3 is a central vertical sectional view of the cylinder and its connected parts taken on a larger scale; and

Fig. 4 is a sectional detail view taken on line 4—4 of Fig. 3. 80

Referring to the drawings, the reference numeral 5 indicates a portion of a motor truck, 6 the side members of the chassis or frame, 7 the cab or seat portion and 8 the tiltable load carrying body of the truck. Said body near its rear end portion is pivotally connected to the opposite side members 6 by pivot brackets 9. 85

The improved horizontal hoist comprises 90 preferably a single cylinder 10 to the forward opposite side portions of which curved side arms 11 are rigidly secured, and the forward ends of said arms are pivotally connected to the bracket members 12. Said bracket members 12 are mounted on the opposite side members 6. The cylinder extends in approximately a horizontal line and is provided with a piston 13 reciprocally positioned therein. A piston rod 14 connected at its forward end 95 100

to the piston 13 extends through the head 15 of the cylinder and at its outer end is provided with an extension 16 having a part-spherical portion 17 and a bolt portion 18 engaged by a nut 19. The bolt portion 18 extends through a tapered opening 20 formed in a medial portion of a yoke member 21 and the spherical portion 17 of the extension 16 extends into a part-spherical socket 22 of the yoke to permit a slight amount of angular adjustment between the extension and the yoke and thus compensates for weaving of the truck chassis. The yoke extends around the rear end and opposite side portions of the cylinder and the end portions thereof are pivotally connected to medial portions of lever arms 23 by pivot pins 24. The lever arms at their rearward ends are pivotally connected to a transverse shaft 25 which is mounted in brackets 26 secured to the opposite side members 6. Rods 27 connected respectively to the brackets 12 and 26 on the side portions 6 brace said brackets in pairs on each side of the chassis, as clearly shown in Figs. 1 and 2.

The forward ends of the lever arms 23 are formed with elongated slots 28 for receiving anti-friction rollers 29 carried by the slotted or bifurcated lower end portions 30 of links 31. For strength the lower portions of the bifurcated ends may be joined together by small transverse parts 32.

The said bifurcated portions are formed with elongated slots 33 for receiving transverse pins 34 which are rigidly connected to the lever arms 23. The upper ends of the links 31 are journaled on a transverse shaft 35 which is mounted in brackets 36 connected to the opposite sides of the body portion 8.

The lever arms 23 and the links 31 swing upwardly to elevate the body, and to compensate for the relative movements between the lever arms, the links and the slots 28 and 33, said slots are of curved formation, as clearly indicated in Figs. 1 and 3, to permit the rollers 29 to move from the inner ends to the outer ends of the slots 28 and the pins 34 to move from the upper ends to the lower ends of the slots 33. This feature of the hoist permits a greater lift of the body with less downward movement of the links and levers to provide greater ground clearance.

The cylinder 10 is formed with a forward duct or port 35' and a rear duct or port 36' which respectively charge or discharge the fluid medium from the cylinder to the front or to the rear of the piston. The port 36' is in communication with a duct 37 formed in the lower wall of the cylinder and extends the length of the cylinder. The forward head 38 is provided with a rotary pump 39, a transverse rotary plug valve 40 and a ball check valve 41.

A duct 42 connects the cylinder duct 37 with the chamber of the pump 39 and the ball

valve 41 is positioned within the duct 35' which connects the chamber of the pump to the cylinder 10 in front of the piston. The ball valve 41 is spring actuated and bears against a seat 43 and is opened by the oil in the cylinder when under pressure from the pump to move the piston rearwardly.

The transverse rotary valve 40 is formed with a duct 44 and the said valve may be manually turned to register its port with the by-pass ducts 45 and 45' when it is desired to by-pass the oil from one side of the piston to the other without the oil passing through the pump. The pump is provided with a downwardly extending arm 46 to which a rod 47 is connected and said rod extends forwardly and is connected to a lever arm control 48 extending upwardly into the cab 7 of the truck.

The pump 39 is of the ordinary two gear type and one of the gears is provided with a shaft 49 having a universal joint connection 50 with a shaft 51 extending to a power take-off 52 of the transmission 53 of the truck. The universal connection of the pump shaft 90 permits the upward movement of the cylinder and the downward swing of the forward end of the pump shaft in tilting the truck body. The operation of the power take-off is controlled by a lever 54 extending into the cab and connected to the said power take-off by a rod 55.

As considerable space within the cylinder is required to accommodate the piston rod 14 when it is in its inner position than when in its outer position and to supply the varying amounts, the rear portion of the cylinder is provided with an oil chamber 56 which comprises an enlargement of the cylinder and is open to the bore thereof the full diameter of said bore. Said head 15 of the cylinder is provided with an inward extension having a cup-shaped end 57 which terminates a slight distance short of the bore of the cylinder to prevent the oil splashing into the chamber 110 when the piston is moving outwardly. An opening 57' is also formed in the cup-shaped extension 57 to permit the more free flow of oil to and from the bore of the cylinder. Said chamber is also in communication with the duct or port 36' by means of a by-pass duct 58. A spring actuated ball check valve 59 is positioned in the duct 58 to permit the oil to flow from the forward side of the piston through the plug valve 40 and the ducts 42, 37, 58 and 58' and into the oil chamber 56 when the piston in its outer position covers the duct 36' and initially starts its forward movement in the cylinder to lower the body. The oil chamber 56 is provided with an air vent in the form of an outwardly opening check valve 60 threaded into the upper portion of the cylinder.

In use the hoist is mounted on a motor truck in approximately a horizontal position 130

and between the truck chassis and the body, as clearly shown in Fig. 1, and when it is desirable to dump the contents of the truck body the transmission controlling rod is operated to transmit motion from the transmission to the pump, and the operation of the pump will draw the fluid medium or oil from the rear of the piston and force it into the bore of the cylinder in front of the piston and force said piston outwardly. The outward movement of the piston will swing the lever arm and the link upwardly and as the upper end of the link is connected to the body it will tilt the body and dump the contents thereof. 15 When the piston has reached its outer position and in which position it closes the port or duct 36', further movement of the piston will be automatically stopped, as the further flow of oil to the pump will be prevented by 20 the piston closing the port 36'. The pump may continue to operate but as its supply of oil is cut off it cannot pump any more into the cylinder in front of the piston. This feature is of great advantage as it eliminates possible damage to the hoist. The piston will remain in its upper position whether or not the pump is in operation. If it is now desired to lower the truck body the valve rod 47 is operated to open the valve 40 and when 25 opened the oil in the cylinder will flow through the ducts 58, 58' and 37 until the piston uncovers the duct 36', and when uncovered the oil will flow directly through the duct 36' and into the cylinder to the rear of the 30 piston, and when the excess oil is forced out of the bore of the cylinder in front of the piston the excess oil will overflow the upper portion of the bore and into the oil chamber at the rear of the cylinder. The speed of 35 lowering the truck body is controlled by opening or closing more or less of the port or duct of the valve.

It is to be understood that any kind of a power medium may be used in lieu of the cylinder, or that any number of cylinders and pistons may be used without departing from the spirit and scope of the invention.

From the foregoing description it will be seen that the horizontal hoist is of very simple construction, is strong and durable and is well adapted for the purpose described.

What we claim as our invention is:

1. The combination with a motor truck having a dump body, of a means for tilting said body, comprising a lever arm pivoted to the truck, a link pivotally connected to the dump body and having a connection with the lever arm, said connection including a pivot carried by each of the connected elements and movable laterally within a slot in the other, and an approximately horizontally extending power means pivotally connected to the truck and having a pivotal connection with the lever arm for tilting said body.

2. The combination with a motor truck having a pivoted dump body, of a means for tilting said body, comprising lever arms pivoted at their rear end portions to the truck, links pivotally connected at their upper ends to the body and depending downwardly therefrom and at their lower end portions pivotally connected to the front end portions of the lever arms, said pivotal connections including concentric pivots carried by each of the connected elements and movable laterally within slots in the other, and a power means pivotally connected to the truck and to medial portions of the lever arms for tilting said body.

3. The combination with a motor truck having a rearwardly tilting body, of a means for tilting said body, comprising spaced apart lever arms pivoted at their rear end portions to the truck, spaced apart links pivotally connected at their upper ends to the body and depending downwardly therefrom and pivotally connected at their lower end portions to the front end portions of the lever arms, said pivotal connections including concentric pivots carried by each of the connected elements and movable laterally within slots in the other, and a power instrumentality interposed between the lever arms and the links and having a pivotal connection with the truck, the said instrumentality having a rearwardly movable member which is pivotally connected to medial portions of the lever arms for tilting the body.

4. The combination with a motor truck having a tiltable body, of a means for tilting said body, comprising spaced apart lever arms pivoted at their rear end portions to the truck, spaced apart links pivotally connected at their upper ends to the body and depending downwardly therefrom and at their lower ends having aligned pivots movable laterally within aligned slots in the forward end portions of the lever arms, an approximately horizontal cylinder pivotally connected at its forward end portion to the opposite side portions of the truck, a yoke extending around the rear end portion of the cylinder and pivotally connected to medial portions of the lever arms, a piston within the cylinder and having a piston rod which extends rearwardly through the cylinder and is connected at its rear end to a medial portion of the yoke, and means driven by the motor of the truck for operating the piston to tilt the truck body.

5. The combination with a motor truck having a tiltable body, of a means for tilting said body, comprising spaced apart lever arms pivoted at their rear end portions to the truck, spaced apart links pivotally connected at their upper ends to the body and depending downwardly therefrom and at their lower ends having aligned pivots movable laterally within aligned slots in the forward end portions of the truck.

the lever arms, an approximately horizontal cylinder pivotally connected at its forward end portion to the opposite side portions of the truck, a yoke extending around the rear end and opposite side portions of the cylinder and pivotally connected at its end portions to medial portions of the lever arms, a piston within the cylinder and having a piston rod which extends rearwardly through the cylinder and has a movable connection with a medial portion of the yoke, and means driven by the motor of the truck for reciprocating the piston and its rod to tilt the truck body.

6. The combination with a motor truck having a dump body, of means for tilting said body, comprising a lever element pivoted to the truck, a link element pivoted to the body, a connection between said elements including a pin carried by each element and movable laterally within a curved slot in the other, a cylinder pivotally connected at its forward end to the truck, a piston within the cylinder and having a piston rod pivotally associated with the body, and means driven by the motor of the truck for operating the piston to tilt the body.

7. The combination with a motor truck having a dump body, of means for tilting said body, comprising a lever element pivoted to the truck, a link element pivoted to the body, a connection between said elements including a pin carried by each element and movable laterally within a slot in the other, and power means operable by the motor of the truck and pivotally connected to the truck and to said lever element for tilting the body.

8. The combination with a motor truck having a dump body, of means for tilting said body, comprising a lever element pivoted to the truck, a link element pivoted to the body, a connection between said elements including a pin carried by each element and movable laterally within a curved slot in the other, and power means pivotally connected to the truck and to said lever element for tilting the body.

In testimony whereof, we affix our signatures.

JULIUS P. HEIL.
